Primary Examiner — Melanie H Tung(74) *Attorney, Agent, or Firm* — Sterne, Kessler, Goldstein & Fox PLLC(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in a sequence, showing our new design;

FIG. 2 is a front view of a second image thereof; and,
FIG. 3 is a front view of a third image thereof.

The broken lines in the Figures showing a display screen or portion thereof are for illustrative purposes only and form no part of the claimed design.

The appearance of the animated image sequentially transitions between the images shown in FIGS. 1-3. The process or period in which one image transitions to another image forms no part of the claimed design.
